WILLIAM C. FROST, OF EAST PITTSBURGH, PENNSYLVANIA.

SECTION-SWITCH.

1,239,464.

Specification of Letters Patent. Patented Sept. 11, 1917.

Application filed April 27, 1915. Serial No. 24,234.

To all whom it may concern:

Be it known that I, HARRY W. DAVIS, a citizen of the United States, and a resident of Swissvale, in the county of Allegheny and State of Pennsylvania, have invented a new and useful Improvement in Section-Switches, of which the following is a specification.

My invention relates to section switches for electric trolley systems, and it has special reference to section switches for use in mine trolley lines, where the trolley conductor is located near the roof of the mine and where it is customary to insert a section-alizing switch in each of the branch conductors that lead from the main trolley line into the side passages or headings.

The object of my invention is to provide a section switch of the above-indicated character that shall be simple and inexpensive in construction, rugged and durable in service, and highly efficient in operation.

In the accompanying drawing, Figure 1 is a side elevational view, with parts broken away and shown in section, of a section switch constructed in accordance with my invention, and Fig. 2 is a transverse sectional view of the device shown in Fig. 1, the section being taken substantially along the line II-II, Fig. 1.

The section switches which have been designed heretofore, and which are in common use in mines and in other trolley systems where it may be necessary to cut a section of the line out of circuit, are usually made up of a large number of parts. They are therefore relatively expensive, especially in view of the fact that switches of this type are seldom operated, being only required for emergency use, as when a mine trolley becomes grounded by a fall of rock or the like. A further disadvantage of the existing forms of section switches is that the sectionalizing is usually accomplished by inserting a block of insulating material between the conducting end pieces or runners, and this insulation must generally be several inches in length, in order to provide sufficient creepage distance between the separated ends of the conductors. When such a device is in service, and the switch is closed, every motor that passes must lose its current for an appreciable interval, and the sudden rush of current that follows when the insulating break is passed is a se-

vere strain upon the motor. Furthermore, it sometimes happens that a heavily loaded car will stop with the trolley wheel resting against the insulating spacing block, and considerable inconvenience and loss of time are caused in again starting the car.

According to my present invention, I avoid all of the foregoing disadvantages, and, in addition, produce a device of extreme simplicity, in which two end pieces or runners are supported upon an insulating block and separated by a relatively short air gap, both sides of which are engaged by a trolley wheel passing the switch. The adjacent ends of the runners are preferably so modified as to provide a long creepage distance between the runners, which are electrically connected by means of a simple form of switch.

For a better understanding of my invention, reference may now be had to the accompanying drawing, which illustrates the preferred form of my invention. Two metallic end pieces or runners 1 and 2 are secured to the lower edge of a block 3, of wood or other suitable insulating material, by means of two short tap bolts 4 and 5 and two longer tap bolts 6 and 7. The bolts 4 and 5 are countersunk in the top of the block 3, in suitable holes which are fitted with plugs 8. The bolts 6 and 7 extend above the block 3 and are provided with flat heads 9 and 10 that are perforated to receive a sliding switch rod 11 to which is attached a handle 12. The hole in the head 9 is slightly tapered in order that the rod 11 may be firmly seated in its contact-making position.

The outer ends of the runners 1 and 2 are provided with the usual openings 13, for receiving line wires 14 and 15, and set screws 16 are disposed in threaded holes transverse to the openings 13 for fastening the line conductors in place. It is to be noted that the trolley connections just described are formed integral with the runners, which is a feature of simplicity and compactness.

The inner ends of the runners 1 and 2 are separated by an air gap 17, which I prefer to make about $\frac{1}{4}$ of an inch wide, but which may be wider or narrower, if desired, without impairing the utility of the device. In order to increase the creepage distance between the runners, I cut away the metal 110

from the upper sides of the adjacent runner ends, as shown at 18. This arrangement does not seriously affect the rigidity of the runners, and provides an ample creepage 5 distance of three inches or more between them, although the air gap is only a fraction of an inch wide. This construction may be varied, if desired, by leaving the ends of the runners intact and cutting away 10 the wooden block to provide the necessary creepage distance, but I prefer the first construction, as shown, since it not only simplifies the outlines of the wooden block, but decreases the weight of metal that is necessary and therefore lessens the cost of the 15 device.

For the purpose of lightening the runners 1 and 2 as much as possible, I prefer to cut away portions from their upper edges, as 20 shown at 19, leaving the full thickness at the points where the fastening bolts 4, 5, 6 and 7 are tapped in. By this means, I make use of a minimum amount of metal, which is usually expensive brass, without sacrificing 25 rigidity or strength.

In order to reinforce the wooden block, transverse bolts 20 and 21 may be passed through suitable openings near the ends of the block, and fastened in place by means of 30 suitable washers and nuts. A hanger 22 may be screwed to the top of the block 3, and wires may be passed through holes in this hanger for the purpose of suspending the switch in its operative position.

The location of the sliding switch, on top of the insulating block 3, is a decided advantage, since the switch rod and handle are protected from damage which may be caused by a trolley pole if the trolley wheel should 35 jump from the wire in the vicinity of the switch. If desired, however, the switch may be placed upon the side of the block, and any other suitable switch may be substituted for the specific form which I have shown 40 and described. I prefer the sliding type of switch for use in mines, because the trolley conductors are usually located so near the roof of the mine that little space is left for operating pivoted knife switches and the 45 like.

In the normal operation of the trolley line in which my improved device is inserted, the sliding switch is closed, the rod 11 being in the position shown. The bolts 6 and 7, together with the switch rod 11 then form a shunt or jumper connection around the air gap 17, and trolley wheels, when they pass across the switch, will engage the runner on the farther side of the air gap before leaving the other runner. The current therefore passes continuously to the motor, without the interruptions and consequent strains upon the motor which I have mentioned above. When it is necessary to cut out of 60 circuit the section of the line on the side of

the switch away from the generator, the switch rod 11 is removed by means of the handle 12. The device then serves as an effective break in the conductor, since the long creepage distance described above prevents current from leaking from one line conductor to the other, and since the air gap 17 prevents direct passage of current. No permanent arc can be maintained across the air gap, even if a car should cross it, for the 70 outer end of the cut-out section is generally dead-ended, and it is only necessary to throw off the controller of the car in order to permanently extinguish any arc that might be struck across the gap.

It is obvious that the details of the structure which I have shown and described may be variously modified by persons skilled in the art without departing from the spirit and scope of my invention, and it is therefore to be understood that no limitations are to be imposed upon my invention except such as are indicated in the appended claims.

I claim as my invention:

1. A section switch for trolley systems comprising a supporting block of insulating material, two longitudinally aligned solid end pieces of conducting material attached to the lower edge of the said block and having their adjacent opposed ends separated only by an air gap sufficiently narrow to permit a trolley wheel to engage both of the said end pieces at once and wide enough to prevent arcing across the air gap under operating conditions, the said adjacent ends of the end pieces being cut away to a substantial extent to provide an increased creepage path around the said air gap, means for attaching trolley conductors to the said end pieces, a plurality of fasteners extending through the said block and serving to attach the said end pieces thereto, and a switch member adapted to electrically connect and disconnect the said end pieces. 90

2. A section switch for trolley systems comprising a block of insulating material, two longitudinally aligned end pieces attached to one edge of the said block and having their adjacent opposed ends separated by an air gap sufficiently restricted to permit a trolley wheel to engage both of the said end pieces at once and sufficiently wide to prevent arcing across the gap under operating conditions, the outer ends of the said end pieces being provided with means for securing trolley conductors thereto, means comprising fasteners extending through the said block and into the said end pieces, for attaching the said end pieces to the said block, the said attaching means serving also as stationary switch contact members, and a movable contact member adapted to connect and disconnect the said stationary contact members. 110

3. A section switch for trolley systems comprising a supporting block of insulating material having downwardly converging sides, two longitudinally aligned solid end pieces of conducting material attached to the narrowed lower edge of the said block and having their adjacent opposed ends separated by an air gap sufficiently narrow to permit a trolley wheel to engage both of the 10 said end pieces at once and without shock, but wide enough to prevent arcing across the air gap under operating conditions, the said adjacent ends of the end pieces being cut away substantially parallel to their trolley-engaging surfaces to a substantial extent 15
- to provide an increased creepage path around the said air gap, a plurality of attaching screws extending through the said block and received in screw-threaded openings in the said end pieces, and a switch member adapted to electrically connect and disconnect certain of the said screws. 20

In testimony whereof, I have hereunto subscribed my name this 26th day of April 1915.

HARRY W. DAVIS.
